UNITED STATES PATENT OFFICE

2,104,118

APPARATUS FOR ATTACHING SHOE SOLES

Charles F. Fitzgerald, Beverly, Mass., assignor
to United Shoe Machinery Corporation, Pat-
erson, N. J., a corporation of New Jersey

Application November 16, 1935, Serial No. 50,174

7 Claims. (Cl. 12—33)

This invention relates to apparatus for attaching shoe soles and especially to the provision of an improved welt holdown mechanism for use in machines by which soles are attached to shoes with cement and pressure.

It is an object of the invention to provide an improved welt holdown which will adequately support the projecting welt and sole extension and which will be capable of applying sufficient pressure to the welt to cause it to adhere securely to the sole without materially interfering with the manipulation of the work or its insertion in or removal from the machine.

A feature of the invention resides in the provision of a welt holdown which is capable of being readily conformed to shoes of different sizes and shapes so that the same holdown can be used upon a variety of shoes by merely making a simple change in adjustment without the necessity of changing any parts.

To this end the illustrated embodiment of the invention comprises a transversely disposed toe piece combined with movable side members having their front ends abutting the shoe engaging face of the toe piece and means for guiding the front ends of the side members for transverse adjustment along the said shoe engaging face. This provides a three-piece holdown which may be readily adjusted to fit the toe portions of shoes of different widths and shapes while maintaining a substantially continuous shoe engaging surface.

Preferably the front ends of the side members are pivotally mounted on supports which are relatively adjustable toward or from each other to vary the width and contour of the toe portion of the holdown, such supports being illustrated herein as consisting of sliding blocks carried by the support for the toe piece of the holdown.

In order to facilitate the application of pressure to the welt of a shoe the holdown support may be arranged to yield downward under pressure applied by the pressure head of the sole attaching machine without changing its adjustment or shape.

Other features and advantages of the invention will become apparent from reading the following detailed description of one embodiment thereof in connection with the accompanying drawing in which

Fig. 1 is a plan view of a portion of a sole attaching apparatus including a welt holdown embodying the invention;

Fig. 2 is a side elevation of the apparatus;

Fig. 3 is a vertical section of a detail of the toe piece taken upon the line III—III of Fig. 1;

Fig. 4 is a vertical section taken upon the line IV—IV of Fig. 1; and

Fig. 5 is a vertical section of a detail of the pressure applying device.

The details of construction of the pad box and pressure head of a sole attaching machine to which the welt holdown of the present invention is illustrated as applied are fully disclosed in an application for United States Letters Patent Serial No. 636,202, filed October 4, 1932, in the names of Milton H. Ballard et al., to which reference may be had for a full description of such details.

In the drawing, 11 indicates the pad support 10 which is shown as consisting of a pad box, and 13 is the pad by which sole attaching pressure is applied to a shoe. Above the pad 13 is a pressure head 15 carrying a toe pad 17 mounted in a toe post 19 with an interposed spring 21 which permits the toe pad to yield upward slightly under heavy pressure. When relative approaching movement of the pressure head 15 and the pad support 11 is effected the toe pad 17 is caused to engage and bear firmly upon the top of the toe portion of the lasted shoe 23 in the machine.

In order to support the welt or sole extension 25 of the shoe against the upward pressure, and in the case of a welt to press it firmly against the surface of the sole being attached, there is provided a novel three-piece welt holdown comprising a toe piece 27 and side members 29, 31. The shoe engaging portions of the sections of the holdown are shaped as shown in Fig. 3 to conform to the welt crease of the shoe and are made of firm but not rigid material, such for example as vulcanized rubber of a suitable degree of hardness.

The toe piece 27 is firmly secured to a curved metal plate 33 of dovetail shape arranged to slide transversely of the shoe in a curved, dovetailed guideway cut in the under face of a toe piece support 35 carried by a vertical pin 37 which is slideable through a supporting plate 39 carried by a gage 41 arranged to engage and be positioned by the toe edge of the sole 43 to be attached to the shoe.

The plate 39 is adjustable longitudinally of the shoe in a housing 45 by a lever 47 in the same manner that the shoe gages are adjusted in the machine disclosed in the Ballard et al. application already referred to. The housing 45 is pivoted at 48 to a forwardly extending member 49 in which is fixed a depending pin 149. The lower end of this pin is engageable in either one of two sockets 51, being held in engagement therewith by a turn button 53 pivoted at 55 upon an arm 57 in the end portion of which the sockets 51 are formed.

The arm 57 corresponds to one of the tip line 55 feeler arms disclosed in the Ballard et al. application, being pivoted for horizontal swinging movement about the pivot 59 and for vertical swinging or yielding movement about a horizontal pivot pin 61.

By engaging the pin 149 in one or the other of the two sockets 51 the toe piece may be moved to extreme positions for long or short shoes, and finer adjustments may be made with the lever 47.

5 The point of a screw 63, which is threaded through the arm 57, rests upon a plate 65, which covers the end portion of the pad 13, and supports the arm at the proper height, while a compression spring 167 surrounding the pin 37 tends 10 to hold the toe piece support 35 up to the plate 39.

The side members of the holddown are sustained and operated by a pair of swinging arms 67, 69 corresponding to the ball-line feeler arms disclosed in the Ballard et al. application. These 15 arms swing horizontally about the pivots 59 and 71 respectively and vertically about horizontal pivots 73 and 75 respectively.

Pivotedly connected to the end of each of the arms 67, 69, as shown at 71, is a horizontal link 20 79 to the outer end of which is pivoted a sole gage carrier 81 from which depend a pair of feelers 83 arranged to engage the edge of the sole 43. Mounted upon the carrier 81 are housings 85 in which are slidably mounted plates 87 25 which may be individually adjusted through the housings by levers 89 in the same manner that the plate 39 is adjusted by the lever 47.

Vertical pins 91 pass loosely through holes in the ends of the plates 87 and are surrounded by 30 springs 93 which support them. To the lower ends of each pair of pins 91 is affixed a supporting member 95 to which the side member 29 or 31, as the case may be, of the holddown is secured at the same level as the toe piece 27.

35 The front ends of the side members 29, 31 abut the shoe engaging face of the toe piece 27 as shown in Fig. 1 and are adjustable toward or from each other along said face to vary the width and shape of the toe portion of the holddown. For this purpose the front end of each support 95 is pivotally connected to a slidable block 97 guided for transverse adjustment in a dovetailed way in the upper face of the toe piece support 35, the pivot 99 comprising a stud having a threaded extension 101 which is screwed 40 through the block 97 until its point bears upon the support 35, locking the block 97 in adjusted position. When it is desired to change the adjustment it is merely necessary to loosen the stud 99, move the block 97 to the desired position and 45 again tighten the stud. When the stud is in tightened condition the support 95 is still free to swing about it as a pivot.

In order to apply pressure to the holddown 50 there is provided a pressure device comprising five radial arms 103 rigidly secured to the toe post 19 sustained by the pressure head 15. One of the arms 103 is arranged over each of the pins 37, 91 and through the end of each arm is 55 adjustably threaded a bushing 105 in which is guided for vertical movement a plunger 107 surrounded by a spring 109 and having at its lower end an enlarged head 111.

The springs 109 are fairly stiff and are of sufficient strength to transmit the desired amount of 60 pressure from the pressure head 15 to the sliding pins 37, 91 and thence to the three sections of the holddown which bear down upon the welt of the shoe. The threaded bushings 105 provide for individual adjustment of the pressure at the various 65 points along the holddown to suit the requirements of the work being operated upon.

In the operation of the apparatus a sole is placed upon the pad 13 and the arms are swung 70 until the gages 41 and 83 engage the sole edge at

the toe and sides, respectively. The welted shoe is then placed upon the sole, the welt holddown members entering the welt crease of the shoe and gaging the position of the shoe relatively to the sole. Pressure is now applied by the machine, the toe pad 17 engaging the shoe and the hold-down pressing the welt firmly down upon the extended margin of the sole with a pressure determined by the adjustment of the plungers 107 and the strength of the springs 109.

10 Having described the invention, what is claimed as new and desired to be secured by Letters Patent of the United States is:

1. A welt holddown comprising a toe piece having a shoe engaging face disposed transversely of the holddown, transversely movable side members having their forward extremities abutting the shoe engaging face of the toe piece, and means for guiding the forward extremities of the side members for transverse adjustment relatively 20 to the toe piece along said shoe engaging face of the toe piece.

2. A welt holddown comprising a toe piece having a shoe engaging face disposed transversely of the holddown, a downwardly movable support for said toe piece, means for yieldingly sustaining the toe piece, and transversely movable side members having their forward extremities abutting the shoe engaging face of the toe piece and sustained for transverse adjustment relatively to the toe 30 piece upon said support.

3. A welt holddown comprising a toe piece and side members disposed in overlapping relation to provide a continuous shoe engaging face, the forward extremities of said side members being pivotally mounted upon and sustained by separate, independently movable supports which are relatively adjustable toward or from each other to vary the width and contour of the toe portion of the holddown.

4. A welt holddown comprising a toe piece having a shoe engaging face disposed transversely of the holddown, a support for said toe piece, blocks slidably adjustable upon said support in a path parallel to the shoe engaging face of the toe piece, 45 means for securing said blocks in adjusted positions, and shoe engaging side members having their front ends pivotally connected to said blocks.

5. In a sole attaching apparatus, a welt hold-down, means for yieldingly sustaining the hold-down, a downwardly movable pressure head, and a series of downwardly spring-pressed plungers carried by the pressure head and spaced above the hold-down in positions to engage and depress the latter upon downward movement of said head.

6. In a sole attaching apparatus, a welt hold-down, means for yieldingly sustaining the hold-down, a downwardly movable pressure head, and 60 a series of downwardly spring-pressed plungers carried by the pressure head and spaced above the hold-down in positions to engage and depress the latter upon downward movement of said head, each of said plungers being independently 65 adjustable vertically to vary the distribution of pressure along the hold-down.

7. In a sole attaching apparatus, a welt hold-down, a series of spring supported pins sustaining said hold-down, a downwardly movable pressure 70 head, and a series of downwardly spring-pressed plungers carried by the pressure head with one of said plungers above each of said pins.
